UNITED STATES PATENT OFFICE

WILLIAM A. GREENFIELD, OF EDMONTON, ALBERTA, CANADA

HAWAIIAN GUITAR

Application filed March 30, 1927, Serial No. 179,427, and in Canada March 23, 1927.

The Hawaiian guitar is a stringed instrument which heretofore has been constructed chiefly along the lines of the Spanish guitar having a hollow body with an opening in the sounding board and having a long and slender neck, the top surface of the neck having a finger-board with frets thereon, the six tonal strings passing over the finger-board, over a nut at the free end of the neck, and extending thence to tuning pegs or other devices in the head. The Hawaiian guitar has several characteristic departures from the ordinary guitar. One is that frets as such are omitted. In place of frets, markers are employed on what would ordinarily be termed a finger board or fret board, these markers being usually inlays and flush with the top surface of the board. The tuned strings must remain free of frets. The tuning and the methods of use are entirely different and distinct, and the music for this instrument is written differently from that written for any other instrument.

The method peculiar to the Hawaiian guitar comprises the application to the upper surfaces of the tonal strings of a metallic plate, ordinarily about an inch in height, an eighth of an inch in thickness, and four inches in length, with a rounded bottom edge, this plate usually being called the "steel." Because of its operation with such a "steel" the Hawaiian guitar is frequently referred to as the "steel guitar."

The Hawaiian guitar is ordinarily played by a person normally seated, as in a chair. The body of the instrument is laid upon the rest surface provided by the top of the right thigh, and the strings are plucked, either by the finger tips direct or by a pointed instrument thimbled upon one finger or more. The variations in tone of the respective strings are produced by applying the "steel" crosswise of the strings at varying distances from the tail-piece, the steel thus becoming in effect a fret movable at will by the operator to define the effective length of the string or strings at any time being vibrated to produce a musical tone or tones.

Through the use of the steel the tones produced by the Hawaiian guitar are decidedly

peculiar to that instrument. To many ears they are harsh and unmusical, and are considered crude. They suggest or demonstrate primitive notions of musical sounds, being wild and bizarre to the cultivated ear. And yet the Hawaiian guitar is capable of producing musical effects of so distinct a type, with its peculiar suggestiveness of the wild and primitive, and with its pronounced capacity for arousing emotions, that it has acquired a distinct status among instruments of its general type and has become very popular in this country. Its popularity is rapidly spreading through European countries.

There are certain objections or deficiencies to and in the Hawaiian guitar of the ordinary type and its musical results, both with respect to its tonal qualities and with respect to its manner of use. Some of these have been alluded to hereinabove. The objects of the present invention are to overcome or lessen the chief of such objections by improving the musical effects of the instrument while rendering its operation more easy, more definite and in general more satisfactory.

In the drawings Figure 1 is a front edge view of my improved Hawaiian guitar with portions broken away to show the continuation and extent of the hollow body, the fragmentary figure of a player of the instrument being also shown to illustrate how the novel guitar is firmly seated on the operator's legs; Fig. 2 is almost a top view of the instrument of Fig. 1, the view being slightly in perspective; and Fig. 3 is a fragmentary sectional view taken through the body extension and key-board as on the line 3-3 of Fig. 1 viewed in the direction of the arrows, showing how the steel is held with respect to the strings.

The main body 10 of the instrument, the tail piece 11, the strings as a whole denominated 12, the nut 13, the head 14, the tuning devices 15, the fret board 16, the opening 17 in the sounding board, and the hand rest 18 may be all in accordance with what is well known in the construction of the Hawaiian guitar as heretofore known. I prefer, however, that the finger buttons of the string-tightening means 15 extend above the head 14, rendering the adjustment of the strings

more easy and while the instrument is held in playing position. An important distinction of the present device from prior practice consists in an elongation of the hollow body through the provision of an extension as 20 thereof. This hollow portion 20 extends preferably to the nut 13. It is preferably materially wider than is the finger-board and to the extent of the finger-board is normally beneath it. Fig. 3 shows that this extension 20 is rectangular in cross view. The sounding board 21 thus extends from end to end of the instrument, as does the bottom wall 22. The side walls of both the body and the extension are shown as being at right angles to the top and bottom walls, and there is an end wall 23 at the head. The construction thus provides a much elongated sound chamber formed of a relatively narrow extension portion and a relatively wide body portion in the particular embodiment shown.

The side of the extension farther from the player is closely adjacent to one longitudinally-extending edge of the finger-board, thus providing clearance on that side for the free manipulation of the steel when it is tilted, as is necessary when playing on the single string adjacent thereto and which is a peculiar and characteristic feature of Hawaiian guitar music.

Fig. 2 shows how the present instrument may lie flat upon the upper legs of a person seated. Since it is thus provided from end to end with a long and flat base it is supported at both ends firmly. Very importantly, when the operator applies the steel, which he does with respect to individual strings or to several or all of them, the finger-board end of the instrument is firmly seated, and the player is not met by a tendency of the instrument to tilt or move in lateral directions due to his manipulations. The required technique may now be exercised free of inhibiting or counteracting influences, and by reason of the firm seating of the instrument the player is able to develop a better technique and to do better execution than without the improvements in that respect.

Turning to Fig. 3 it will be noted that the left hand of the operator holding the steel is resting on or near the corner at the juncture of the sounding board 21 and what may be termed the inner wall 25 of the extension 20. The steel has an appreciable weight and its handling in time becomes tiresome, especially to younger folks and female performers. While operating according to these improvements the hand rests from time to time and sometimes slides along the rest surface provided by the extension 20, as shown in Fig. 3. A better manipulation of the steel can also be had in some instances with the hand so resting, and certain technical effects can thereby be produced with more certainty and more

easily than where the whole arm is swinging freely.

Another important feature of the improvement is in the advantage of better tonal effects in general. I have discovered that one reason for the harshness and decidedly metallic character of the tones of the ordinary Hawaiian guitar is in the hitherto relatively small reverberatory air column or space defined by the body walls, considering the kind and character of this instrument. I have found that by increasing the air column within the body in the longitudinal direction of the instrument, producing a relatively long air column, the tones are rendered deeper and richer and notably free of metallic harshness. In this respect I have thus produced a "steel guitar" having tones relatively rich in musical qualities, tones having excellent timbre, resulting from the harmonious blending of overtones, and tones which, while fully characteristic of this instrument, are pleasing to the ear.

Note the nose-like projection 28 midway between the ends of the instrument where the extension side 27 meets the side of the body. This projection is a distance indicator for use of the player as his hand moves over the strings. It is at the twelfth tone marker on the finger-board, which indicates the octave. It is highly important for the operator to play this octave with certainty and exactness and in a rapid movement. The projection mentioned serves to show him this place by the sense of touch.

The manufacture of my new guitar may be in accordance with practices well understood in the art.

I contemplate as being included in these improvements all such variations, changes, departures and modifications from what is thus specifically illustrated and described as are included in the scope of the accompanying claims.

I claim:

1. A Hawaiian guitar comprising side, top, bottom and end walls forming a wide hollow body and a narrow hollow extension thereof, a finger-board having the transversely arranged tone-indicating markings of a Hawaiian guitar secured on the top of said extension and directed longitudinally therewith, there being means for holding and tightening six tonal strings extending substantially parallel to each other above the finger-board, said means including a nut and a tail-piece adapted to hold said strings at a materially great distance from said finger-board whereby the strings will be maintained free of the finger-board under pressure by a playing "steel" upon the strings applied in the direction of the finger-board, one edge of said finger-board extending longitudinally closely adjacent to one side of said extension.

2. The combination of claim 1 hereof in which the other side of said extension, and which is the one closer to the player's body when the instrument is normally in use, is at a substantial distance from that part of the finger-board immediately under the tonal strings.

5 3. The combination of claim 1 hereof in which the top and bottom walls of the body and extension are substantially parallel with each other and provide a substantially flat surface on the bottom of the instrument from end to end thereof.

10 4. The combination of claim 1 hereof in which there is a distance-indicating extension of the body at approximately the twelfth tone marker on the finger-board and at the side of the instrument body normally farther from the player's body.
